MULTIPLE SLIDING DRAWER DISPLAY DEVICE

Roscoe L. Ford, Los Angeles, Calif.

Application December 20, 1947, Serial No. 792,951

12 Claims. (Cl. 312—337)

1

This invention relates to apparatus comprising a plurality of drawers adapted for the display of various articles adapted to be conveniently disposed in drawers, or for the convenient storage of such articles.

Heretofore, the usual practice in the disposition or storage of small articles adapted to be placed in drawers for access at varying intervals was to place them in drawers which are separately mounted in cabinets in such manner that they are, for the most part, adapted to be withdrawn so as to display the contents of only one drawer at a time. Even though two or more drawers be extended, nevertheless, it was only the contents of the upper drawer that were readily available.

In developing the present invention, it has been the principal object to provide a series of drawers slidably mounted upon one another so that the whole series may be extended whereby to expose for display purposes the contents of all the drawers, should that be required.

Another object of the invention is to provide a construction for an extensible series of display drawers particularly adapted for the transport and display of heavy articles of merchandise, such as small machine tools and the like, the structure being capable of withstanding the rigors of such transportation and use.

Another object is to provide an extensible series of drawers especially adapted to contain a large number of small articles, whereby a large display area may be provided in a comparatively small space, for example, in the storage space provided in the rear of an automobile under a conventional lid.

Another object of the invention is to employ in the construction of such display devices a plurality of channel bars so slidably inner-related that no space is required vertically except that occupied by the bottoms of the drawers and the display spaces between the various drawer bottoms.

A further object of the invention is to provide in such construction a novel roller arrangement by means of which the channel bars of adjacent drawers are supported by rollers engaging with flanges constituting portions of the channel bars of neighboring drawers.

It is an additional object of the invention to provide for roller supporting means in drawer construction of the indicated type wherein channel bars are employed so that the forward ends of the upper drawers will be supported by the resting of their flanges upon rollers carried upon

2

the side walls of channel bars of the lower drawers, and also such that the rear ends of the drawers are carried upon the upper flanges of the lower drawers by means of rollers affixed to such rear ends of the upper drawers. It is an incidental object of such arrangement to provide for proper distribution of the weight of the upper drawers both when the drawers are closed and when they are extended to the limit of their extension when in display position.

It is a still further object of the invention to provide a drawer construction and arrangement whereby channel bars of adjacent drawers may be oppositely faced so as to inter-fit and thereby 15 reduce to a minimum the space required both laterally and vertically for the disposition of the supporting and positioning means.

Other objects of the invention, and various features of the construction, will become apparent to those skilled in this art upon reference 20 to the accompanying drawing wherein one embodiment of the invention is disclosed for the purpose of illustration.

In the drawing:

25 Fig. 1 is a perspective view showing in extended position a drawer assembly of this invention which is mounted in the rear compartment of an automobile;

Fig. 2 is an elevation of the front end of the drawer assembly when in closed or non-extended position;

Fig. 3 is a side elevation as viewed from the left of Fig. 2;

35 Fig. 4 is a fragmentary vertical transverse section as approximately indicated by the line 4—4 of Fig. 3, a portion of the left corner of the upper drawer being broken away; and

Fig. 5 is a similar fragmentary vertical transverse section as indicated by the line 5—5 of Fig. 3.

40 The drawing illustrates the rearward portion of an automobile 10 having a luggage compartment or storage compartment provided with a floor 12 and adapted to be enclosed by a conventional door or lid 14.

45 The sliding drawer assembly of this invention is shown as comprising an uppermost drawer 15 which slides upon an underlying drawer 16, the drawer 16 in turn sliding upon another underlying drawer 17, the drawer 17 sliding upon a fixed bottom drawer 18 which is secured to the compartment floor 12. These various drawers are adapted to be moved between an extreme extended position substantially as illustrated in Fig. 1 and an entirely closed or collapsed posi-

tion where they may be locked in place as illustrated in Fig. 3.

Each of the drawers 15, 16, 17, and 18 is provided with a vertical front wall 20 to which appropriate handles 21 are attached, each drawer being also provided with a vertical rear wall 22, and with a substantially flat bottom 23 which may have upstanding flanges 24 welded or otherwise appropriately secured to the various metal parts constituting the front, rear, and side walls 10

of the respective drawer. Each of the drawers 15, 16, 17, and 18 is provided with side walls which are, in general, in the form of channel bars which constitute runners for the respective drawers, as best seen in Figs. 4 and 5, the flanges 24 of the various drawer bottoms 23 being respectively secured thereto, as above indicated. In the case of the drawer 15, these sides are composed of channel bars 25 which are specifically indicated as being of angle bar formation and having only lower longitudinal flanges 25a integrally secured along the lower edges of the longitudinal vertical webs comprising the body portion of the bars 25. However, if required for the purpose of strength or otherwise, the bars could be true channel bars with upper longitudinal flanges. In the case of the drawers 16, 17, and 18 the sides are respectively formed of longitudinally extending channel bars 26 having integral upper and lower flanges 26a, channel bars 27 having integral upper and lower flanges 27a, and channel bars 28 having integral upper and lower flanges 28a. As illustrated, the various flanges 26a, 27a, and 28a are horizontally disposed and therefore at right angles to the vertically disposed webs of the various channel bars. It will be noted that the lower flanges of the channel bars 25, 26, and 27, respectively, underly the upper flanges of the channel bars 26, 27, and 28 next below. The assemblage is secured to the floor 12 of the automobile compartment through the medium of the lower flanges 28a of the lower channel bars 28 and bolts 30 which pass through the floor 12 and slots 32 in the flanges 28a. These slots provide for a corresponding amount of longitudinal adjustment of the drawer assembly.

Support of the rearward end of each drawer upon the rearward end of the drawer next below is effected through the medium of rearward rollers 35 and the respective flanges, and support of the forward end of each drawer upon the forward end of the drawer next below is effected through the medium of forward rollers 36 and the respective flanges. As illustrated, the roller 35 is secured to the respective wall of the web of each of the channel bars 25, 26, and 27, these rollers resting respectively upon the upper flanges 26a, 27a, and 28a of the channel bars 26, 27, and 28 next below. This relationship is best illustrated in Fig. 5. At the forward ends of the drawers the rollers 36 are secured to the respective side walls of the channel bars 26, 27, and 28, the lower flanges 25a, 26a, and 27a of the respective drawers next above resting upon these rollers 36 whereby to carry the weight of the drawer next above in each instance. All of the rollers 35 and 36 are mounted on stub shafts 37 threaded or otherwise suitably fixed in the respective channel bars.

Inasmuch as it is desirable to have one or more of the upper drawers, such as the drawer 15, shorter than the lower drawers, so as to expose the corresponding forward portion of the drawer next below in each instance, another roller 36 is

required rearward of the respective forward roller 36, in order that the forward end of the respective upper drawer, for example, drawer 15, may be supported when the drawers are in closed position as indicated in Fig. 3. The forward rollers 36 in such cases are required for the purpose of providing a proper support when the respective upper drawer is extended to display position as seen in Fig. 1.

Particular attention is directed to the fact that the channel bars 25, 26, 27, and 28 as best seen in Figs. 4 and 5, are arranged in staggered relation so that alternate bars in the vertical series face in one direction and the intervening bars face in the opposite direction. This requires a minimum of lateral spacing and also a minimum in vertical height, while at the same time causing the horizontal flanges of adjacent channel bars to provide guides or tracks for one another as well as tracks for engagement by the rollers 35 and 36. All the rollers 35 at each side of the assembly are thus provided in one vertical series, and all the rollers 36 at the other side are provided in another vertical series, the series of rollers 35 at one side being positioned directly behind the corresponding series of rollers 36.

In order that the rollers 35 at the rear ends of the channel bars 25 and 27 may engage with the upper faces of the upper flanges 26a and 28a of the channel bars 26 and 28, adjacent portions of the respective drawer bottoms 23 are necessarily apertured as indicated at 38 to pass such rollers 35 as seen in Fig. 5. It will be noted that the edge portions of the bottoms 23 of these two drawers are provided with additional bent portions 39 which are required to clear the adjacent flanges 26a and 28a of the channel bars 26 and 28 (Figs. 4 and 5).

For limiting movement both forward and rearward of any upper drawer with respect to the drawer next below it, stops 40 are welded to the rearward portions of the underfaces of the flanges 25a and 27a of the channel bars 25 and 27 in such positions that these stops 40 will strike the respective forward rollers 36 on the channel bars 26 and 28 when the drawers 15 and 17 are drawn forward with respect to the drawers 16 and 18. Similarly, a stop 42 is welded to the upper side of each of the upper flanges 27a of the channel bars 27 whereby these stops 42 will be struck by the rearward rollers 35 carried at the rear of the channel bars 26 of the drawer 16, forward movement of the drawer 16 with respect to the drawer 17 being thereby limited at its extreme outer position. For the purpose of checking the return movement of each of the sliding drawers, the rear ends of the drawers 16, 17, and 18 are provided with stops 43 which will be respectively struck by the rear ends of the drawers 15, 16, and 17 as they reach the limit of their return movement and the place where they are to be locked in closed position. These stops 43 are, of course, welded to the rear end of the respective channel bars 26, 27, and 28 project upward into position 60 to be engaged by the corresponding ends of the overlying channel bars 25, 26, and 27.

For the purpose of latching the sliding drawers 15, 16, and 17 in their closed or non-display position, an elongated locking pin 45 is provided for each side of the assembly, the upper end of each locking pin 45 having a laterally offset handle piece 46. When the drawers are in the position illustrated in Fig. 3, these pins 45 are adapted to be passed through series of aligned locking 70 holes 48 disposed approximately centrally in all

of the flanges 25a, 26a, and 27a as well as in the lowermost flanges 28a of the channel bars 28 bolted to the floor 12 of the automobile compartment or other support. Thus, when the locking pins 45 have been passed through all of the holes 48, including those in the lowermost flanges 28a, longitudinal shift of the drawers is prevented against any strain short of that which would shear off the pins 45 at a point between contiguous or overlapping flanges.

For the purpose of steadyng a heavy load when the drawers are extended to full display position as illustrated in Fig. 1, a pair of weight carrying legs 50 is provided. One end of each of these legs 50 is pivotally secured to the front wall 20 of one of the drawers, these legs 50 replacing the handles 21 otherwise employed on the drawers. In the instance shown, the legs 50 are mounted on the front wall of the drawer 17, and the necessary swinging mounting is accomplished through the medium of eyes 52 on the upper ends of the legs 50, which eyes are disposed upon pivot studs 53 and retained in any suitable manner such as by cotter keys. When the legs 50 are swung down into operative supporting position as shown in Fig. 1, they bear upon the supporting surface through the medium of appropriate feet 54, and when they are swung up into the inoperative position shown in Fig. 2, they are retained by an appropriate pivoted spring clip 55 or the like. As illustrated, the length of each leg 50 is approximately the width of the drawers or a little less than the spacing between the two pivot studs 53, and in connection with practically all automobiles it is possible to mount these legs either upon the front of the drawer 17 or the front of the drawer 16 so as to maintain proper elevation of the extended drawers with respect to the street or other pavement and with regard to the height of the floor 12 of the automobile compartment.

With reference to the use of the sliding drawer assembly of this invention, its normal transport assembly is illustrated in Fig. 3. Here the drawers 15, 16, and 17 are retracted to their return limit, as determined by the stops 43, and the elongated locking pins 45 are passed through the various holes 48 in the flanges of the channel bars 25, 26, 27, and 28, the locking pins 45 on both sides of the drawer assembly being used.

When it is desired to withdraw any of the drawers for display purposes, the locking pins 45 are removed and laid aside. If it is desired to extend all of the drawers to display position, the handle 21 of the drawer 15 is grasped and drawn forward. When the stops 40 of this drawer reach the respective forward rollers 36, which limit the movement of the drawer 15 on the drawer 16, continued draft causes the drawer 16 to be drawn forward until the rear rollers 35 thereon meet the stops 42 on the upper flanges of the channel bars 27 of the drawer 17, whereupon the drawer 17 is drawn forward until its stops 40 meet the rollers 36 on the drawer 18. This last position represents the maximum extension of the drawer assembly. At this point, or at any appropriate intermediate point, the legs 50 will be swung down to give the necessary additional support. It will be observed that the rearward ends of the channel bars 25, 26, and 27 of the drawers 15, 16, and 17 extend back an appreciable distance beyond the respective rear walls 22 of these three drawers in order to provide proper bearing leverage for each upper drawer upon the forward end of each drawer im-

mediately below it. Thus, although the ends of the channel bars of an upper drawer extend rearward from the forward portions of the channel bars immediately below, nevertheless the contents of the entire lower drawer are in each instance made visible. Since the rear end wall 22 of the lower drawer 18 may be placed at the extreme rear of the respective channel bars 28, the lower drawer 18 is effectively longer than the display portion of the upper drawers.

It is desirable in some instances to have one or more of the upper drawers shorter than the next lower drawer, as previously indicated, and under such circumstances the forward portion 15 of such lower drawer extends forward beyond the next drawer above so that such forward portion of a drawer immediately below an upper drawer is open to inspection without the moving of the upper drawer. This is especially beneficial where 20 adjacent drawers of different depths are desired to display materials of different sizes, for example, larger materials than are found in the top drawer, without moving an upper drawer.

When it is desired to return the drawers to the closed position of Fig. 3, it is necessary merely to press rearward upon the front of the drawer 15, such drawer 15, when it reaches its innermost position with respect to the drawer 16 by reason of having engaged the respective stop 43, being adapted to pick up and return the drawer 16 until it reaches a similar position with respect to the drawer 17 which is then returned to closed position over the drawer 18. The supporting legs 50 will have been meanwhile raised into the inoperative position shown in Fig. 2. Complete closure having been effected, the elongated locking pins 45 are dropped into the holes 48. Thereupon the automobile compartment lid 14 may be closed, so that the salesman may continue his itinerary.

Since many modifications of the generic invention will no doubt occur to those skilled in this art, it is intended to cover all such variations as fall within the scope of the claims.

45 I claim as my invention:

1. A sliding drawer assembly comprising in combination: a plurality of relatively shallow superimposed drawers adapted to be drawn forward upon one another, the sides of each drawer comprising a pair of opposed channel bars having webs and flanges, the webs being vertically disposed and the flanges horizontally disposed, the channel bars of adjacent drawers being faced in opposite directions, a lower flange of each upper bar underlying the upper flange of the next lower bar; a forward roller disposed on the forward end of each channel bar of each lower drawer and upon which roller rests said lower flange of each upper bar; and a rearward roller disposed at the rearward end of each channel bar of each upper drawer, each such rearward roller resting upon the upper flange of the respective channel bar of the next lower drawer, the various rollers providing for drawing each upper drawer forward upon the next lower drawer to expose the contents of such next lower drawer.

2. A combination as in claim 1 wherein a lock stem is provided which is adapted to pass through holes in the flanges of the channel bars of all the drawers when aligned in closed position.

3. A combination as in claim 1 wherein stops are provided on the various drawers to limit the forward and rearward movement of each upper drawer with respect to the next lower drawer.

4. A combination as in claim 3 wherein said

stops are positioned to engage the respective forward rollers.

5. A combination as in claim 3 wherein a lock stem is provided which is adapted to pass through holes in the flanges of the channel bars of all the drawers when aligned in closed position.

6. A combination as in claim 1 wherein said rollers are mounted upon stub shafts horizontally fixed in the webs of the respective channel bars.

7. A combination as in claim 1 wherein the rearward channel bar ends carrying said rearward rollers extend beyond the rearward ends of some of the drawer bodies whereby to expose portions of said drawer bodies between the respective rearward rollers and channel bar ends.

8. A drawer assembly comprising in combination: a plurality of superimposed drawers adapted to slide forward one upon another, the sides of each drawer comprising channel bars having vertically disposed webs and horizontally disposed flanges, the channel bars of adjacent drawers being oppositely faced and such bars being thereby alternately arranged vertically, the lower flange of an upper bar being below the upper flange of a lower bar; and means movably supporting adjacent flanges in sliding relationship.

9. A combination as in claim 8 wherein a lock stem is provided which is adapted to pass through holes in the flanges of the channel bars of all the drawers when aligned in closed position.

10. A combination as in claim 8 wherein stops are provided on the various drawers to limit the forward and rearward movement of each upper drawer with respect to the next lower drawer.

5 11. A combination as in claim 8 wherein rollers are provided upon various of the drawers to receive flanges of adjacent drawers to support the weight of the latter.

10 12. A combination as in claim 8 wherein the rearward channel bar ends of one drawer extend beyond the body of said one drawer to expose a portion of the next lower drawer between said ends.
